ANDIRON FOR FIREPLACES

Eugene C. Schoenheit, Portland, Oreg.

Application January 11, 1949, Serial No. 70,198

1 Claim. (Cl. 126—298)

1

This invention relates generally to heating appliances and particularly to an andiron for fireplaces.

The main object of this invention is to produce an improved form of andiron in which the portion most subject to deterioration can be easily replaced without replacing the entire andiron.

The second object is to so construct the andiron that it will provide a wide spread for the ornamental posts on the outside of the fireplace screen and at the same time hold the log supporting feet at a desired distance.

The third object is to provide a set of andirons wherein the foregoing objects are attained without the use of long and difficult castings and in which the parts will knock down to a convenient shipping size.

The fourth object is to so construct the andirons that they will be extremely rigid and will require the minimum amount of labor to assemble the same for use.

The fifth object is to make an andiron which will set solidly on any hearth without subjecting the parts to strain under the action of heat.

I accomplish these and other objects in a manner set forth in the following specification as illustrated in the accompanying drawings, in which:

Fig. 1 is a perspective view of the andiron base with the ornamental front removed.

Fig. 2 is a perspective view of the unit requiring most frequent replacement.

Fig. 3 is a plan of a pair of andirons with the ornamental units cut away in horizontal section.

Fig. 4 is a fragmentary front elevation of a fireplace screen with the ornamental members in front of same.

Fig. 5 is a section taken along the line 5—5 in Fig. 3.

Like numbers of reference refer to the same or similar parts throughout the several views.

Referring in detail to the drawing, there is shown a fireplace screen 10 in front of which are the ornamental units 11 which it is desired to space farther apart than are the supports on which the logs rest.

The supports consist of a horizontal bar 12 having a hearth engaging foot 13 at its rear end and a log stop 14 on its top side directly above the foot 13.

At the forward end of each bar 12 is mounted the upturned log stop 15, under which is the

2

downturned tapering shank 16. A key lug 17 is formed on the rear side of the shank 16 at its junction with the bar 12.

A curved foot member 18 has one straight end 5 which terminates in the upturned standard 20 having a slot 21 formed therein. The standard 20 is secured to the unit 11 by means of the bolts 22.

The foot member 18 has formed thereon, opposite the standard 20, a socket 23 which is tapered 10 to receive the shank 16. The socket 23 has formed in its top side a key slot 24 which receives the key lug 17.

It can be seen that by making the sections 12 and 18 separable at the shank 16 and socket 23, a 15 number of very desirable results are attained. Not only has the manufacture been simplified but it is possible to replace any burned or broken parts without replacing the entire andiron. More important still, owing to the socket connection, the curved foot member 18 and the foot 13 all find uniform support on the surface of the hearth.

I claim:

An andiron consisting of a curved elongated horizontal hearth engaging foot member having 25 an upturned socket at one end and means for attaching an ornamental post at its other end in combination with a horizontal log supporting bar having upturned log stops at its ends and a downturned socket engaging shank at one end and a downturned hearth engaging foot at the other 30 end thereof and means for holding said bar and curved foot member in alignment.

EUGENE C. SCHOENHEIT.
